FRANK L. McCORMICK, OF NORTH TONAWANDA, NEW YORK, ASSIGNOR TO THE
RUDOLPH WURLITZER MANUFACTURING COMPANY, OF NORTH TONAWANDA,
NEW YORK, A CORPORATION OF NEW YORK.

MECHANISM FOR CONTROLLING AUTOMATIC MUSICAL INSTRUMENTS.

1,191,205.

Specification of Letters Patent. Patented July 18, 1916.

Application filed August 25, 1913. Serial No. 786,393.

To all whom it may concern:

Be it known that I, FRANK L. McCORMICK, a citizen of the United States, residing at North Tonawanda, in the county of Niagara and State of New York, have invented new and useful Improvements in Mechanism for Controlling Automatic Musical Instruments, of which the following is a specification.

- 10 This invention relates to mechanism for controlling automatic musical instruments and other devices or machines operated by a coin-controlled motor, and more particularly an electric motor.
- 15 It sometimes happens that persons deposit coins in the chute during the playing of a selection, especially when a number of coin-receptacles or "slot-boxes" are placed at tables or other convenient stations in restaurants or other public places, for starting the instrument from different parts thereof. Such receptacles include a chute containing switch terminals of the motor circuit which are bridged by the deposit of a nickel or other proper coin, closing the circuit and causing the instrument to play. By the use of ordinary coin chutes, the instrument will not play additional tunes upon the deposit of such extra or additional coins, and in order 20 to give all patrons full value for their deposits in such cases, controlling devices of various kinds have been devised to cause the instrument to play a selection for every coin deposited, regardless of whether a number 25 of coins are dropped into the chutes at the same time or at different times during the playing of a piece.

The object of my invention is the provision of an improved controlling device of 40 this character which shall be simple, compact and inexpensive in construction and reliable in operation.

In the accompanying drawings: Figure 1 is a front view of the controlling device with 45 the front plate of the casing removed, and showing the motor switch closed. Fig. 2 is a similar view showing the motor-switch open. Fig. 3 is an inside view of the ratchet wheel showing the spring for turning it backward.

50 Similar characters of reference indicate corresponding parts throughout the several views.

1 indicates the box or casing which encloses the parts of the device.

2 indicates the electric motor of the automatic musical instrument or other machine or apparatus to be controlled. The motor circuit is controlled by a switch of any suitable construction, that shown in the drawings consisting of a vertically-swinging 55 switch-lever 3 connected with one terminal 4 of the motor circuit and coöperating with a contact spring 5 connected with the other terminal 6 of said circuit. This switch-lever is connected by a link 7 with a vertically-swinging actuating lever 8 pivoted at 9 to the casing 1. A spring 10 which connects the lever 8 with a fixed part of the casing tends to close the switch lever 3. The actuating lever 8 is swung in the proper direction to 70 open the switch lever by a trip pin or projection 11 carried by a rotary member or ratchet wheel 12 mounted on a stud 13 which projects from the rear wall of the casing. This ratchet wheel is constantly urged to turn 75 backwardly by a spiral spring 14 arranged within said wheel which is made hollow or barrel-shaped for this purpose, the spring being attached at its inner end to said stud and at its outer end to the barrel of the 80 wheel, as shown in Fig. 3.

15 indicates a spring-pressed detent for preventing backward rotation of the ratchet wheel 12. This detent or pawl is provided with a tail 16 which projects into the passage 85 of a coin chute 17, so as to be tripped out of engagement with the ratchet wheel to release the latter, when a coin 18 is dropped into the chute.

19 indicates a feed pawl adapted to move 90 the ratchet wheel 12 forward intermittently to cause its pin 11 to approach and trip the tail of the actuating lever 8. This feed pawl is guided by a fixed stud 20 against which the back of the pawl slides, the pawl being provided on opposite sides of the stud with stop shoulders 21 which limit its reciprocating movement. At its free end, this pawl has a nose or cam 22 which on the forward stroke of the pawl rides over a fixed pin or projection 23, whereby the tooth 24 of the pawl is raised out of contact with the ratchet wheel 12, while on its rearward stroke the pawl clears said pin and is moved into engagement with the ratchet wheel by a spring 25. 100

In the preferred construction shown in the drawings, the feed pawl 19 is actuated by a small bellows or pneumatic 26 to the mov-

able board of which it is pivoted at 27. This pneumatic is controlled by the perforated music sheet 28, the tracker board 29 and a pneumatic valve action of any ordinary construction. That shown in the drawings comprises a wind chest 30 containing the customary suction chamber 31 from which the air is constantly exhausted during the playing of the instrument; a chamber 32 with 10 which the pneumatic 26 is connected by a conduit 33 and which is alternately exhausted and flushed by the action of the usual suction valve 34 and flushing valve 35. These valves are mounted on a common stem 15 which is actuated by the usual diaphragm or pneumatic 36, the chamber beneath this diaphragm being connected by a tube 37 with one of the tracker ducts 38. This duct co-operates with a row of perforations, one of 20 which is shown at 39, such a perforation being usually arranged at the end of each selection of the music sheet.

The operation of the controlling device is as follows: Normally, the switch lever 3 is open, breaking the motor circuit, as 25 shown in Fig. 2, the lever being held in this position by the engagement of the trip pin 11 with the tail of the actuating lever 8, and the spring 10 being strained ready to 30 close the switch lever upon the release of the actuating lever. When a coin is deposited in the chute 17, the detent 15 is momentarily tripped out of engagement with the ratchet wheel 12, allowing the latter to turn the distance of one tooth or step, whereupon the 35 detent pawl reengages the wheel and prevents its further rotation until the deposit of another coin. By this backward rotation of the ratchet wheel, the trip pin is withdrawn from the actuating lever 8, allowing 40 the spring 10 to depress the same and closing the switch lever, as shown in Fig. 1, causing the instrument to play. If no additional coins are deposited during the playing 45 of the first selection, the pneumatic 26 is deflated at the end of that selection by the registration of the first controlling perforation 39 of the music sheet with the corresponding tracker duct, thereby moving the 50 feed pawl 19 forwardly, turning the ratchet wheel 12 the distance of one tooth and causing the pin 11 to trip the lever 8 and open the switch lever 3, as shown in Fig. 2, stopping the instrument. If, however, a second 55 coin is deposited during the playing of the first selection, the detent 15 is again tripped, allowing the spring 14 to turn the ratchet wheel 12 backward the distance of another tooth and causing the trip pin to recede the 60 same distance from the tail of the actuating lever 8, thus removing said pin two steps from said lever. Under these conditions, after the playing of the first selection, the pneumatic 26 is deflated and the ratchet 65 wheel and its trip pin are turned forward

one step or tooth, but as this pin is still another step away from the actuating lever 8 it does not trip the same by this actuation of said pneumatic. The instrument therefore plays the second selection, and at the end 70 thereof the pneumatic is again deflated by the registration of the second controlling perforation 39 with the corresponding tracker duct, thereby advancing the ratchet wheel and its pin a second step, causing 75 said pin to trip the switch lever to its open position and stopping the instrument after having played two selections for the two coins deposited. Should additional coins be deposited during the playing of either of 80 said selections, the trip pin 11 will be caused to recede another step for each additional coin. This pin thus retreats one step from the actuating lever 8 for each coin deposited and is advanced one step at the end of each 85 selection played by the instrument, but the pin does not trip the actuating lever and open the motor-switch until a piece has been played for the last coin deposited. The controlling device thus insures the playing 90 of at least one selection for every coin deposited, giving every patron full value for his deposit.

In the operation of the device as above described, it is assumed that the coins are 95 deposited directly in the chute 17 arranged in the casing of the controlling device.

If desired, the device may be controlled from a distance by placing the customary coin-receptacles or coin-boxes at the desired 100 stations. In this case, an electro-magnet 40 is located in the casing and its armature 41 is arranged to engage the heel 42 of the detent 15, so that when the magnet is energized the detent is disengaged from the 105 ratchet wheel 12 by the attraction of the armature in the same manner in which this is effected by the deposit of a coin acting upon the tail 17 of the detent. This magnet is included in a circuit containing the contact 110 terminals 43 of said coin-boxes, so that whenever a coin is deposited in one of these boxes, it bridges the terminals thereof, as shown by dotted lines in Fig. 1, closing the magnet-circuit and withdrawing the detent, 115 as above described.

I claim as my invention:

1. In a device of the character described, the combination of a switch, a single ratchet-wheel having a trip-pin controlling said 120 switch, a feed pawl arranged to engage said wheel for turning it forwardly, a pneumatic for actuating said pawl, a spring tending to turn said wheel backwardly, and a coin-controlled detent also engaging said wheel.

2. In a device of the character described, the combination of a coin chute, a switch lever, a single ratchet-wheel having a trip-pin, an actuating lever connected with said switch-lever and arranged in the path of 130

said trip-pin, a spring connected with said lever and tending to close said switch-lever, a feed pawl arranged to engage said wheel for turning it forwardly, a pneumatic for actuating said pawl, a spring tending to turn said wheel backwardly, and a detent also engaging said wheel and having a trip-

member which projects into said coin chute.
Witness my hand this 18th day of August
1913.

FRANK L. McCORMICK.
